UNITED STATES PATENT OFFICE.

HORACE J. RIDOUT, OF FLORESVILLE, TEXAS.

RAILROAD-CROSSING SIGNAL.

1,400,458.

Specification of Letters Patent. Patented Dec. 13, 1921.

Application filed January 31, 1921. Serial No. 441,327.

To all whom it may concern:

Be it known that I, HORACE J. RIDOUT, a citizen of the United States, residing at Floresville, in the county of Wilson and 5 State of Texas, have invented a new and useful Railroad-Crossing Signal, of which the following is a specification.

This invention aims to provide novel means whereby a highway signal may be 10 raised and lowered automatically, at a railroad crossing, by a passing train.

With the above and other objects in view, which will appear as the description proceeds, the invention resides in the combination 15 and arrangement of parts and in the details of construction hereinafter described and claimed, it being understood that, within the scope of what is claimed, changes in the precise embodiment of the invention shown 20 can be made without departing from the spirit of the invention.

In the drawings:—

Figure 1 shows in top plan, a device constructed in accordance with the invention; 25 Fig. 2 is a side elevation wherein the signal is raised; Fig. 3 is a section on the line 3—3 of Fig. 1, the signal being lowered; Fig. 4 is a cross section on the line 4—4 of Fig. 1; Fig. 5 is a horizontal section taken through 30 one rail and showing one of the operating members in bottom plan.

The numerals 1 and 2 denote the rails of a track, the ties appearing at 3. A first operating member 4 in the form of a lever, is fulcrumed at 5 on the rail 1. A retractile spring 6 is connected at one end to the lever 4, below the fulcrum of the lever, the spring being connected at its opposite end to one of the ties 3. A second operating member 35 7 is provided, the same being fulcrumed intermediate its ends, as shown at 8, on the rail 1. The fulcrum element 8 carries a spacer 28, interposed between the operating member or lever 7 and the rail 1, as shown 40 in Fig. 5. A latch 9 is fulcrumed intermediate its ends, as shown at 10, on the rail 1. A retractile spring 11 is connected at one end to the latch 9 below the fulcrum of the latch, the opposite end of the spring being 45 connected to one of the ties 3. The latch 9 is carried by a bracket on the rail 1, the bracket having a stop 70 which limits the swinging movement of the latch, responsive to the spring 11. The numeral 12 marks a 50 spring keeper having an upstanding finger or projection 32. The keeper 12 is adapted,

at one end, to interlock with the lower end of the latch 9, the opposite end of the keeper being securely mounted, as indicated at 14, on the right of way. Guides 15 of any desired construction are carried by some or all of the ties 3. A connection 16 is mounted for reciprocation in the guides 15. The connection may comprise a cable connected to the lower end of the operating member 4, 60 the element 16 extending into a slot 18 in the lower end of the second operating member 7. A securing element 19 extends across the slot 18 and is mounted in the operating member 7, one end of the element 17 being 65 mounted on the securing member 19. The part 19 carries a link 20 connected pivotally to a rod 21. The rod 21 is connected pivotally to the latch 9, below the fulcrum 10 of the latch. 70

The rails 1 and 2 are supplied with bearings 22, a bearing post 23 being located in alinement with the bearings 22, transversely of the track 1—2. The numeral 24 denotes, generally, a shaft, which is a composite 80 structure. The shaft 24 includes a part 25 journaled in the bearings 22, and a part 26 journaled in the post 23, the parts 25 and 26 of the shaft being connected by a torsion spring 27. An arm 29 is secured to the 85 arm 25 of the shaft 24 and is located inside the rail 1, in close relation thereto. The arm 29 co-operates with a stop 87 on the rail 1. 90

The numeral 30 marks a vertically swinging member having angularly disposed arms 31, located on opposite sides of the post 23, the arms, and consequently the member 30, being connected to the part 26 of the shaft 24. The numeral 33 denotes an extension, 95 pivoted at 34 to the arms 31 of the member 30. The extension 33 may be U-shaped, and in the bend of the extension, a weight 35 is secured as shown at 36. One of the arms 31 of the member 30 has a stop 37 with 100 which the extension 33 engages. A signal 36 is pivoted at 39 to the member 30, the said member carrying a projecting shield 40.

Standards 41 are mounted closely adjacent to the post 23. The standards 41 are 105 surrounded by compression springs 42, exerting an upward pressure on a bar 43 which is slidably mounted on the standards. The upward movement of the bar 43 under the action of the springs 42, is limited by nuts 110 44 on the standards 41. A post 45 is disposed in the same vertical plane with the

member 30 and carries a compression spring 46 on its upper end.

- When the member 30 is raised, as shown in Fig. 2, the lower end of the signal 38 is housed behind the shield 40. The arms 31 of the member 30 rest on the bar 43, the bar 43 being pushed downwardly on the standards 41, and the springs 42 being compressed, the function of the springs being to return the signal from a raised position to a lowered position, under conditions which will be pointed out hereinafter. The extension 33 rests on the ground, out of engagement with the stop 37 as shown in Fig. 2. The extension 33 and the element 35 constitute a counterpoise for the member 30. When the member 30 starts to swing from a raised position toward a lowered position, the extension 33 is out of engagement with the stop 37, for a time. When the member 30 arrives nearly at the raised position shown in Fig. 2, the end of the extension 33 rests on the ground for a time, before the member 30 arrives completely in a raised position. In view of the foregoing, it will be clear that the counterpoise 33-35 exercises its function at the proper time but does not, on the one hand, impede the movement of the member 30, when said member starts to move to a lowered position, nor, upon the other hand, does the counterpoise act on the member 30 when said member is almost in a raised position, and requires no counterpoise action. When the member 30 is in a raised position, the arm 29 on the shaft 24 is in an approximately horizontal position and is interengaged with the latch 9, as indicated in Fig. 2, the spring 11 being under increased tension. The free end of the spring keeper 12 rests against the end of the latch 9, as shown in Fig. 2, but is not interlocked positively with the latch, as shown in Fig. 3. Suppose that a train is moving along the track 1-2 in the direction of the arrow A. The first wheel of the train coacts with the operating member 4 and tilts the operating member. The connection 16 is pulled, the latch 9 is tilted and disengaged from the arm 29, the shaft 24 being set free for rotation, responsive to the spring 27, and the arm 29 engaging the stop 87. The springs 42 react on the bar 43, the bar 43 is thrust upwardly, and the member 30 is swung toward a lowered position. After the member 30 passes the vertical, said member swings downwardly by its own weight, the spring 46 on the post 45 acting as a buffer. The signal 38 swings out from behind the shield 40, and exercises its obvious function. When the latch is tilted as aforesaid, the spring keeper 12 interlocks with the lower end of the latch, as shown in Fig. 3. The latch 9 is prevented from moving, responsive to the spring 11, and there is no pull, due to the spring, on the connection 16. As a conse-

quence, the operating member 4 remains in the position of Fig. 3, and does not extend upwardly far enough so that it can be struck forcibly by every passing wheel.

The foremost wheel on the train arrives at length upon the second operating member 7, the cable 16 being carried to the right (Fig. 3) and the operating member 4 being restored to the upright position of Fig. 2. The foremost wheel engages the arm 29 and rotates the shaft 24, excessive jar or shock being avoided, owing to the presence of the spring 27. The member 30 is swung to a raised position, the extension 33 assumes the position of Fig. 2, the bar 43 is slid downwardly by contact with the arms 31 of the gate, and the springs 42 are compressed. The torsion spring 27 is strong enough so that it overcomes the springs 42 and puts them under compression when the rotation of the shaft 24 is begun. When the springs 42 have been compressed, continued rotation of the shaft 24 places the spring 27 under tension. The arm 29 swings downwardly toward a horizontal position and engages, first, the finger 32 on the spring keeper 12. The keeper 12 is disengaged from the latch 9, and the latch 9 is rendered responsive to the spring 11. The spring 11 swings the lower end of the latch 9 to the right (Fig. 3) until the lower end of the latch engages the stop 70. The latch 9 now is so positioned that, when the arm 29 is swung downwardly, far enough, the free end of the arm will interlock with the latch 9, the member 30 being held in a raised position.

If desired, the member 30 may be so shaped and mounted that, when the member 30 swings to a closed position, the shield 40 or the signal 38 will not descend into an automobile or other vehicle which happens to be beneath the member 30 at the time that the same moves downwardly.

I claim:

1. In a device of the class described, a car-actuated operating member; a movable latch; a connection between the operating member and the latch; a shaft supported for rocking movement; a signal member connected with the shaft; a car-actuated arm on the shaft and engageable with the latch; and a keeper engaging the latch, the keeper comprising a part responsive to the movement of the shaft to disengage the keeper from the latch while the arm is moving toward engagement with the latch.

2. A device of the class described, constructed as set forth in claim 1, and further characterized by the fact that said part of the keeper is in the form of an upstanding finger disposed in the path of the arm.

3. In a device of the class described, a car-actuated operating member; a movable latch; a connection between the operating member and the latch; a shaft supported for

rocking movement and comprising coöperating parts; a torsion spring connecting said parts of the shaft; a signal member connected with one part of the shaft; a 5 car-actuated arm on the other part of the shaft and engageable with the latch; and means responsive to the movement of the shaft for disengaging the keeper from the latch while the arm is moving toward engagement with the latch.

4. A device of the class described, constructed as set forth in claim 3, and further characterized by resilient means for initiating the movement of the signal member 15 toward a lowered position, said means being rendered potential by the movement of the signal member toward a raised position.

5. A device of the class described, con-

structed as set forth in claim 1, and further characterized by the provision of a counterpoise pivoted to the signal member, the signal member having a stop which engages the counterpoise and transfers the weight thereof to the signal member when the signal member approaches a lowered position, 25 means being provided for taking the weight of the counterpoise off the stop, when the signal member approaches a raised position.

In testimony that I claim the foregoing as my own, I have hereto affixed my signature 30 in the presence of two witnesses.

HORACE J. RIDOUT.
